PORTABLE CRANE

Hal Hayes, Los Angeles, Calif., assignor to Hayes
Econcrete Corporation of America, Reno, Nev.,
a corporation of Nevada

Application July 12, 1937, Serial No. 153,180

6 Claims. (Cl. 214—86)

This invention relates to apparatus for use in connection with building operations, and particularly pertains to a portable crane.

In various building operations in which concrete is used, especially as the building material, and particularly in connection with structures such as concrete houses, the walls of which are progressively cast upon the foundation as the building structure is made, it is desirable to provide a portable crane structure which will elevate the concrete to a height above the point at which it is to be poured into suitable forms and which makes it possible for means to be quickly provided at a desired location for setting up a crane in association with a concrete mixing machine, and to utilize the power of an engine of the motor vehicle upon which the concrete mixer and the crane are carried to operate the concrete mixer and the elevating means for delivering the concrete to the crane and discharging it therefrom in a desired placed position.

The present invention contemplates the provision of a motor vehicle upon which a concrete mixer is mounted and a collapsible tower and crane construction which may be disposed in an operative unfolded position when its use is desired, and which structure may then be driven by the power plant of the vehicle to produce its necessary operating functions.

30 The invention is illustrated by way of example in the accompanying drawings in which:

Figure 1 is a view in side elevation showing the vehicle with the tower and the crane thereon, said elements being disposed in their extended and operating positions.

Fig. 2 is a view in side elevation similar to that of Fig. 1, showing the tower and the crane in their collapsed positions ready for transit.

Fig. 3 is a view in diagram in side elevation showing the crane partially folded and indicating a second position of folding in dotted lines.

Fig. 4 is a diagrammatical view in side elevation showing the crane completely folded and indicating an intermediate folded position in dotted lines.

Fig. 5 is a fragmentary view in elevation showing the clutch and worm drive for operating the raising and lowering mechanism of the tower.

Fig. 6 is a view in end elevation showing the tower and the crane unfolded and ready for operation and further indicating the bracing of the tower.

Fig. 7 is an enlarged fragmentary view showing the construction of one of the tower braces.

55 Fig. 8 is a view in plan showing the assembled

tower structure in the condition disclosed in Fig. 6, and with the turn table and the crane removed.

Fig. 9 is a sectional view in plan through the tower as seen on the line 9—9 of Fig. 1.

Fig. 10 is a view in plan through the tower as seen on the line 10—10 of Fig. 1.

Fig. 11 is a view in top elevation showing the crane and the turn table mounted upon the tower.

Fig. 12 is an enlarged view in plan showing the power transmission units as generally indicated in Fig. 10.

Fig. 13 is a view in section and elevation as seen on the line 13—13 of Fig. 12 and discloses the brake and the clutch control mechanism.

Fig. 14 is a view in central longitudinal section as seen on the line 14—14 of Fig. 12 and discloses the clutch mechanism in the crane drum.

Fig. 15 is an enlarged fragmentary view showing a control for certain of the operating mechanism.

Fig. 16 is an enlarged view in section and elevation showing a reversible hoist drive.

Fig. 17 is a fragmentary view showing an automatic brake structure embodied in the device.

Referring more particularly to the drawings, 10 indicates a motor truck having a power plant which is generally indicated at 12, but which is not shown in detail due to the fact that such power plants are the usual combustion engine and transmission of a motor vehicle. Suitably connected with the transmission of the motor vehicle is a drive shaft 13 which operates various units of the present structure. The structures mounted upon the frame of the vehicle for operation are

30 a tower 14, a concrete mixing device 15, and a bucket or skip 16 with its operating mechanism. The tower comprises a plurality of vertical uprights 17 which are rigidly secured to the frame 18 of the vehicle and which uprights are shown

35 as spaced equidistant from each other to occur at the corners of a square area. The uprights are preferably in the form of structural angles. Slidably mounted within the angle uprights 17 are extension uprights 19. The extension up-

rights 19 are suitably braced together by cross braces 20 to provide a rigid structure of square horizontal section which may be moved bodily

40 within the tower structure comprising the lower uprights 17. A suitable driving mechanism is

45 provided for this structure, as will be hereinafter described.

Carried upon the frame structure including the extension members 19 is a hopper 21 into which material may be placed and from which it may

be withdrawn through a discharge spout 22. This discharge spout has an extension pipe 23 connected therewith and is closed with a gate 24 at its discharge end. Carried by a horizontal frame element 25 is a pair of guide rails 26 which are spaced from each other and receive rollers 27 mounted on a hoist bucket 28. The upper end of the guide rails 26 are bifurcated so that the rollers 27 may swing with relation to each other and tip the bucket. A lower extension 29 of the guide rails 26 are rigidly connected with a platform 30 of the tower structure 17 and permit the bucket 28 to move to a position where material from the cement mixer 15 may be discharged thereinto. 10

15 The bucket 28 is raised and lowered by suitable driving means to be hereinafter described. Mounted upon the top of the upper tower extension 19 is a turn table 31. This turn table is adapted to rotate in a horizontal plane and is 20 fitted at its edge with an annular gear 32 which meshes with a gear 33 by which the turn table may be rotated. Mounted upon the rotating element of the turn table is a pair of bearing blocks 34 carrying a horizontal king pin 35. This king pin 35 pivotally connects the bearing blocks 34 and the turn table 31 with a foot 36 of a boom 37. The boom 37 comprises a pair of arm sections 38 and 39 which are hinged together at 40 and may swing through a vertical plane with relation to 30 each other to assume a collapsed or extended position. Mounted upon the rotating element of the turn table is a mast 41 which is held by boom stays 42 which are connected with horizontal brace arms 43 fixed to and lying horizontally upon the upper face of the turn table 31. These arms as particularly shown in Fig. 11 of the drawings are disposed at an angle to each other and provide a rigid support for the outer ends of the stays 42 so that the mast 41 may be suitably 40 braced for a purpose to be hereinafter described. Mounted at the upper end of the mast 41 is a hanger 44 for a sheave 45. Attached to the hanger 44 is a cable 46 which is led around a block 47 attached to a hanger 48 on the outer boom section 39 by a hook 49. The cable is then led over the sheave block 45 and down through the hopper 20 to the hoisting drum 50, the details of which will be later described. The boom 37 carries a bearing structure 51 at its free outer end and this bearing structure in turn carries a pulley 52. The pulley 52 receives a cable 53, one end of which is attached to a traveling block 54 and the other end of which is led down through the tower to a winding drum 55. A cable 56 is attached to the opposite side of the traveling block 54 and is led down to the opposite side of the drum 55. In fact the cable lengths 53 and 56 may represent a continuous cable wound around the drum 55 so that when one length is wound on to 50 the drum the other length will be wound off of the drum to shift the traveling block 54. The traveling block 54 embraces the lower edge of the boom 37 and is fitted with rollers 57 which ride along the lower channeled flange 58 of the boom. 55 A pulley 59 is carried by the traveling block and over this pulley a cable 60 is led. The cable carries a suitable hook 61 to receive the bucket 16. The cable 60 is led over one of a set of pulleys 62 on the turn table and is then led downwardly to a winding drum 63 of the transmission unit. 60

The winding drums 55 and 63 are freely mounted upon a shaft 64. At opposite ends of the drums are spiders 65 and 66. The spider 65 is keyed upon the shaft carrying the drum 55 and 70 75 disposed in a plane circumscribed by the drum.

Clutch shoes 67 are pivotally mounted upon the outer ends of the arms of the spider 65 and may engage the inner circumference of the drum 55. This is accomplished by links 68 which are pivoted to the shoes 67 and also to a shifting collar 5 69. The collar 69 is splined on to the shaft 64 and may be shifted by a shifting arm 70 which is pivoted upon a pin 71 carried by a bracket 72 of the frame structure 13. The pin 71 also carries an operating arm 74 which is connected to a 10 reach-rod 75 and a shackle 76. The rod 75 is also connected with a rod 77. This rod extends to an operating arm 78 of a pivot pin 79 carried by a bracket 80 at the opposite end of the winding drum 63. The pin 79 also carried a shifting 15 lever 81 which engages a collar 82 splined upon the shaft 64 at the outer end of the drum 63. Links 83 are pivoted to the collar and also to shoes 84 which may be expanded into the end of the winding drum 63 to lock the drum and the 20 clutch spider 66 together. The lever arms 74 and 78, as shown in Figs. 13 and 14, connect with crank plates 85 carrying links 86 and 87. These links are attached to brake bands 88, one of which encircles each of the winding drums 55 and 63. A 25 tension spring 89 acts to hold the crank plates 85 and their links 86 to apply tension upon the brake bands. The lever arrangement is such as to insure that the brakes will be released when the clutches are set and will be set when the clutches 30 35 are released. The spider 66 carries a gear 90 and since the spider 66 is keyed to the shaft 64 the gear 90 will rotate therewith. This gear is in mesh with a gear pinion 91 carried upon a shaft 93 housed in suitable bearings upon the frame 73. 35 Mounted upon the outer end of the shaft 92, as shown in Fig. 12, is a clutch collar 93 which is splined on to the shaft and may be shifted by a lever 94. Disposed at opposite sides of the clutch collar are gear pinions 95 which are in mesh with a gear 96. Thus when the collar 93 is shifted longitudinally of the shaft 92, the shaft 92 may be driven in opposite directions. The lever 94 is mounted upon a pin 97 to which a lever 98 is secured. This lever is fitted with a reach-rod 99 at its free end which rod connects with an operating lever 100 to be hereinafter described. The drum 50 is fitted with a brake band structure 101 and is provided with a clutch mechanism 102 similar to that previously described and shown in Fig. 13. This clutch operatively connects the drum 50 with the shaft 103 which carries the drum 50 and which shaft is rotatably supported in bearings 104 on the frame. A shifting yoke 105 is provided to shift the clutch mechanism into and out of position. This yoke is provided with a lever 106 attached to an operating rod 107 by which it may be moved. The operating rod connects with a draw bar 108. 40

By reference to Fig. 15, a particular arrangement for separately operating certain of the clutch levers is shown. It will be seen that the lever 78 is provided with a pin 109 to which rods 77 and a rod 110 are attached. Each of these rods is formed with a slotted opening to receive the pin. The rod 77 as has been previously described is operated in unison with the rod 75 through the bar 76. The rod 110 is operated through the bar 111. By this arrangement the bar 76 may be operated to simultaneously actuate both of the drums 55 and 63, but if desired the rod 110 may be actuated through the rod 111, to 50 55 60 65 70 75 80 85 90 95 removable shaft which is temporarily supported intermediate its ends in a bearing 113 on the platform 30. The upper end is supported by an upper frame structure 114 and carries the gear pinion 33 which drives the large gear 32 by which the boom is swung in a horizontal plane. The lower end of the shaft 112 is fitted with a coupling 115 which attaches the removable shaft to a continuing shaft 116. The shaft 116 carries a brake mechanism 117 shown in Fig. 17, and which will be hereinafter described. The shaft 116 also carries a bevel gear 118 which is freely mounted thereon. This gear is in constant mesh with an idler gear 119 carried upon a stub shaft 120. The bevel gear 119 is also in constant mesh with a bevel gear 121. The bevel gear 121 is keyed on to a shaft 122. The shaft 122 carries a worm gear 123 which is in mesh with a driving worm 124. The driving worm is freely mounted on a drive shaft 125 and may be connected to the drive shaft 125 through a clutch 126 splined on to the shaft 125. The shaft 125 is suitably connected with the power transmission mechanism through the shaft 13. The shaft 122 is keyed to the gear 121 as previously described. This gear has a clutch element adapted to be engaged by a movable clutch collar 127. The movable clutch collar is splined on to the lower end of the shaft 116 and when in engagement with the clutch face of the gear 121 will cause the shafts 116 and 122 to be locked together so that the shaft 116 will rotate in one direction. The gear 118 which is freely rotatable upon the shaft 116 and is in constant driving engagement with the gear 119 is fitted with a clutch face which may be engaged by the clutch collar 127 to lock the gear to rotate with the shaft 116. In this position the shaft 122 will drive the shaft 116 through gears 121, 119, and 118. This will produce reverse rotation of the shaft 116. The collar 127 is engaged by a shifting yoke 128 which is pivoted upon a pin 129 carried by a bracket on the housing of the reversing gear structure. The yoke 128 is secured integral with a bell crank lever having an arm 129 and an arm 130. The arm 129 is attached to a draw bar 131 as shown in Fig. 12 of the drawings. The arm 130 is attached to a pitman rod 132, pivotally secured to a disc 133. The disc is mounted upon a pivot 134 and is formed with wedge-shaped cam faces 135 as shown in Fig. 17. The disc is disposed between end extensions 136 of a brake band which circumscribes the brake drum forming a part of the brake mechanism 117. The band is supported directly upon a bracket 137. The pivot 134 carries a pair of heavy springs 138 which act against the members 136 and tend to hold the brake in its set position and the shaft 116 against rotation. It will be evident, however, from examination of Fig. 17, that when operating the clutch collar 127 in either direction from its neutral position the disc 133 will be rotated to wedge the ends of the brake band apart and permit driving operation of the shaft 112. The various operating rods 108, 76, 131, 111 and 100 are operated by their respective levers indicated generally at 140 in Figs. 1 and 8.

The upper section of the tower is raised and lowered by cables 141 which are led over suitable pulleys 142 and 143 and are driven by a sprocket 144. When the tower is in its erected position as particularly shown in Fig. 6 of the drawings, brace arms 145 are provided. These arms are pivoted to the lower section of the tower at 146 and are pivoted at their lower ends

to shoes 147. The arms 145 are preferably tubular having upper and lower sections telescoping into each other as shown in detail in Fig. 7. These sections may be adjustably set by placing a pin through perforations in the telescoping member in any desired extended position. The lower end of each of the arms 145 is fitted with a screw 149 engaging a nut 150 carried by a bracket 151 which is pivoted at 152 to a casting 153 mounted upon the shoe 147. The casting 153 carries a similar fitting 154 pivoted at 155 and by which another brace structure 156 is connected with the shoe. This brace structure is similar in design to the brace arms 145 and is fastened to the frame of the hoist by brackets 157. In order to hold the vehicle rigid so that it will not rest upon its spring suspension, jacks 160 are disposed at opposite ends of the vehicle frame as shown in Fig. 1, and temporarily support the same. The hoist bucket 28 is provided with raising and lowering means which comprises a cable 161 led over pulleys 162 carried by the frame member 114 and connected to the bottom of the bucket on the far side from the concrete mixer 15. This cable is led down and around a guide pulley 163 which is wrapped on a winding shaft 164 mounted on the frame, and suitably driven through a sprocket chain 165 from a sprocket 166 connected with a worm gear 167 and controlled by a clutch 168.

In operation of the present invention the entire crane assembly is mounted on a truck in its collapsed position, as shown in Fig. 2 of the drawings. When it is desired to set up the crane for operation the boom is unfolded from the position shown in Fig. 2 so that the boom section 38 may swing downwardly and around to assume a position in alignment with the boom section 39. A bolting plate 41 is then fastened to the adjoining edges of the two boom sections 38 and 39 on opposite sides from the hinge 40 so that the boom will stand in a horizontal and rigid position. It is then supported by the cable 46 and the tackle 45 and 47. The cable is then led down around its drum in the base of the tower. When the structure is in this position the levers 140 may be controlled by the operator standing on the platform 30 and when these levers are selectively operated the various cables will be wound and unwound to elevate the tower, to raise and lower the bucket 28, and to horizontally and vertically shift the bucket 16 to receive and dump the material disposed of into it from the hopper 20. After the crane has been used and it is desired to fold the boom the operation may be performed as shown in Figs. 3 and 4. Here it will be seen that the extended boom is brought to rest on a frame structure 170 as shown by solid lines in Fig. 3. The cable 46 is then drawn to move the boom sections 38 and 39 into folded positions as indicated in dotted lines in Fig. 3. This movement continues until the sections 38 and 39 swing vertically and parallel after which the folded boom structure may be lowered to the solid line position indicated in Fig. 4. Here it may be secured by a fastening hook 171. The outer end of the boom may then be supported by a brace 172 so that the structure is ready for transportation to some other location.

It will thus be seen that the structure here disclosed provides a compact and efficient means of mixing, conveying, and placing concrete and similar materials, the structure being so adapted as to be readily transported as a single unit and moved from one job to another.

While I have shown the preferred form of my invention, as now known to me, it will be understood that various changes might be made in the combination, construction and arrangement of parts, by those skilled in the art, without departing from the spirit of the invention as claimed.

Having thus described my invention, what I claim and desire to secure by Letters Patent is:

- 10 1. A portable unit of the class described comprising a motor vehicle, an extensible tower carried thereby, a turn-table at the top of the tower, a boom carried thereby, said boom comprising a plurality of foldable sections, means for supporting the boom in its unfolded and operative position, means for driving the turn-table to swing it in a horizontal plane, power control means for operatively connecting said driving means and the power plant of the vehicle, means for elevating material to the top of the tower, and means for conveying the material to a point of discharge on the boom.
- 15 2. A portable unit of the class described comprising a motor vehicle, an extensible tower carried thereby, a turn-table at the top of the tower, a boom carried thereby, said boom comprising a plurality of foldable sections, means for supporting the boom in its unfolded and operative position, means for driving the turn-table to swing it in a horizontal plane, power control means for operatively connecting said driving means and the power plant of the vehicle, means for elevating material to the top of the tower, and means for conveying the material to a point of discharge on the boom, and control means for operatively connecting the elevating means with the power plant of the vehicle to drive the same.
- 20 3. A device of the character described, the combination of: a vehicle, a power means disposed on said vehicle, an extensible tower carried by said vehicle, a turn-table rotatably mounted on said tower, a boom connected to said turn-table, said boom comprising a plurality of foldable sections, means for supporting said boom in its unfolded and operative position, means connecting between said power means and said turn-table and operable to swing said turn-table in a horizontal plane, means for elevating material to the upper part of said tower, and means for conveying the material to a point of discharge on said boom.
- 25 4. A device of the character described, the combination of: a supporting base, power means on said base, a tower supported on said base and

comprising upper and lower sections disposed in telescopic relation one with the other, a turn-table rotatably mounted on said upper tower section, a boom connected to rotate with said turn-table, said boom being formed of a plurality of foldable sections, means for supporting said boom in its extended and operable position, means connecting between said power means and said turn-table for swinging said boom around the vertical axis of said turn-table, means for elevating material to the upper section of said tower, and means for conveying the material to a point of discharge on said boom.

5. A device of the character described, the combination of: a portable base, a power plant disposed on said base, an extensible tower associated with said base, a turn-table rotatably mounted on the top of said tower, a boom comprising a plurality of foldable sections secured to said turn-table, means for supporting said boom in its unfolded and operative position, means for driving said turn-table to swing it in a horizontal plane, control means connecting between said drive means and said power plant for controlling the operation of said turn-table, means for elevating material to the upper part of said tower, means for conveying the material from the upper part of said tower to a point of discharge on said boom, and control means for operatively connecting the elevating means with said power plant.

6. A device of the character described, the combination of: a portable base, a power plant disposed on said base, an extensible tower associated with said base, a turn-table rotatably mounted on the top of said tower, a boom comprising a plurality of foldable sections secured to said turn-table, means for supporting said boom in its unfolded and operative position, means for driving said turn-table to swing it in a horizontal plane, control means connecting between said drive means and said power plant for controlling the operation of said turn-table, means for elevating material to the upper part of said tower, means for conveying the material from the upper part of said tower to a point of discharge on said boom, control means for operatively connecting the elevating means with said power plant, and control means connecting between said elevating and conveying means and said power plant for controlling the operation of said elevating and conveying means.
